Application September 15, 1947, Serial No. 141,396
In Canada July 15, 1947

Term of patent 14 years

(Cl. D54—6)

To all whom it may concern:

Be it known that we, Joseph Marcel Marisseau and Rosaire Duval, citizens of the Dominion of Canada, residing in the city of Montreal, Province of Quebec, Dominion of Canada, have invented a new, original, and ornamental Design for Twin Lathe, of which the following is a specification, reference being had to the accompanying drawings, forming part thereof.

Figure 1 is a perspective view showing the top, one side and one end of a twin lathe embodying our new design; and

Figure 2 is a perspective view showing the top, the other side and end thereof.

The dominant features of our design reside in the portions shown in full lines.

We claim:

The ornamental design for a twin lathe, as shown and described.

JOSEPH MARCEL MARISSEAU.
ROSAIRE DUVAL.
